UNITED STATES PATENT OFFICE.

ALFRED L. KRONQUEST, OF CHICAGO, ILLINOIS, ASSIGNOR TO CONTINENTAL CAN COMPANY, OF SYRACUSE, NEW YORK, A CORPORATION OF NEW YORK.

RECEPTACLE.

Application filed August 9, 1921. Serial No. 490,892.

To all whom it may concern:

Be it known that I, ALFRED L. KRONQUEST, a citizen of the United States, residing at Chicago, in the county of Cook, State of Illinois, have invented certain new and useful Improvements in Receptacles, of which the following is a description, reference being had to the accompanying drawing and to the figures of reference marked thereon:

10 The invention relates to new and useful improvements in receptacles, and more particularly to a metal container having an open top which is closed by a cover after the contents have been placed in the container.

An object of the invention is to provide a container with a closure which may be quickly and very easily applied to the body portion of the container by very simple operating devices.

A further object of the invention is to provide a container wherein the cover is secured to the body portion of the cover by the deflecting of the flange of the cover so as to contract or indent the side of the body portion of the container.

A still further object of the invention is to provide a container having a cylindrical body portion, the edge of which is reinforced or strengthened by the bending of the metal thereof, and wherein the cover is secured to the body portion of the container by the bending of the cover flange intermediate its edges so as to cause the cover to indent or contract the side wall of the body portion of the container, along a line below the strengthened edge.

These and other objects will in part be obvious and will in part be hereinafter more fully disclosed.

In the drawings which show by way of illustration one embodiment of the invention:—

Figure 1 is a side view of a cylindrical receptacle embodying my improvements;

Fig. 2 is an enlarged sectional view of a portion of the side wall and a portion of the cover, the cover being shown as detached from the container body;

Fig. 3 is a similar view but showing the cover as placed on the container body preliminary to the closing or attaching of the cover to said can body, and

Fig. 4 is a view similar to Fig. 3 but showing the cover secured to the can body by the

bending of the flange of the cover intermediate its edges.

The invention consists broadly in a receptacle having a body portion which is preferably cylindrical in transverse cross section. Said body portion has its upper edge strengthened by the rolling of the metal forming the body portion of the container into an inturned bead or rib. The cover is formed with a central depressed portion and a depending flange, thus forming a pocket which is U-shaped in cross section adapted to fit over said inturned bead or strengthening rib on the body portion of the container. A suitable sealing material or packing may be placed in the upper portion of the pocket for causing a tight sealing of the can. Said depending flange on the cover is for the greater portion of its extent substantially vertical. The extreme lower edge portion, however, is bent outwardly. The parts so constructed are assembled and after the cover has been placed on the body portion of the container, the outwardly turned portion of the flange is engaged by suitable devices and folded upwardly and then the upwardly folded portion of the flange, together with the lower part of the flange above the bend therein, is crowded or deflected inwardly so as to indent or contract the vertical side wall of the can body along a line directly beneath the strengthening bead on the vertical wall, and thus the cover is tightly secured to the body portion of the container.

Referring more in detail to the drawings, I have shown my invention as applied to a container consisting of a cylindrical body portion 1 to which is attached a bottom portion 2 by double seaming, soldering or any other suitable means. The body portion of the container is open at the top. Said body portion is preferably cylindrical in cross section, and at the extreme upper edge of the body portion, the side wall is rolled into a bead 3. This bead may be a tight roll or a comparatively loose roll such as is sometimes referred to as a false wire, or it may be bent in other ways in order to strengthen the upper edge of the body portion of the container. Said container is preferably made of sheet metal, although it will be obvious that from certain aspects of the invention said container body may be made of fiber, paste board or any other suitable material.

The open top of the container is closed by a cover 4. Said cover has a central depression forming a vertical wall 5, and a depending flange which also provides a substantially vertical wall 6, the lower edge portion 7 of which is turned outwardly at an angle to the vertical wall 6. These vertical walls 5 and 6 are, of course, joined by the metal of the cover forming the U-shaped 10 pocket, in the upper portion of which may be placed a suitable sealing material 8.

It is noted that the vertical side wall 9 of the body portion 1 is substantially straight from the bead 3 thereof to the bottom of the container, and particularly in the region directly beneath the strengthening bead 3. When the cover is placed on the body portion of the cover, the vertical wall 5 of the cover engages the inner face of the 20 bead 3 and the vertical wall 6 of the cover engages the outer face or outer wall of the body portion of the container. The bead 3 substantially closes the U-shaped pocket and confines the sealing material 8 so that when 25 the cover is crowded on to the container body, the sealing material will make a tight joint between the cover and container body. The cover is held pressed on to the container body, and while so seated, the out-turned 30 portion 7 of the flange is bent upwardly to the position shown in Fig. 4, and this, together with the immediate part of the vertical portion 6 of the flange on the cover directly above the bend in the flange are 35 forced or deflected inwardly indenting the side wall of the container body as indicated at 10 in Fig. 4. This indenting or contracting of the container body along a line directly beneath the strengthening bead 3, 40 draws the cover tightly down on to the bead 3 and firmly holds the cover on the container body. The folding up of the metal in the flange reinforces the lower edge of 45 the flange and makes a very strong grip of the cover on the container body.

While I have shown the edge of the flange as folded up during the securing of the cover to the container body, it will be obvious that the invention, so far as the container is concerned, resides in strengthening the lower edge of the flange, either by bending while closing or before closing, and deflecting the strengthened thickened edge for indenting or contracting the container body along a line directly beneath the bead or strengthening upper edge of the container body for securing the cover to the container body. This strengthened lower edge of the flange may be made in various ways, but is preferably made by a reciprocating flared ring,

such as shown for example in my co-pending application, Serial Number 490,893, filed of even date herewith, wherein my process of closing a container is more fully set forth and claimed.

65

It is obvious that minor changes in the details of construction may be made without departing from the spirit of the invention as set forth in the appended claims.

Having thus described the invention, what 70 I claim as new and desire to secure by Letters-Patent, is:—

1. A receptacle including in combination, a body portion having a cylindrical wall and 75 inturned bead at its upper edge, a cover for said body portion having a depending flange and a central depression forming a U-shaped pocket with substantially vertical walls adapted to receive said bead, with said vertical walls frictionally engaging the inner 80 and outer portions of said bead, the lower edge portion of said flange being normally inclined outwardly and downwardly with the bend in the flange at a point below the bead in the vertical wall of the can body, 85 whereby the inclined portion of the flange may be bent upwardly while the cover is on the receptacle and the part of the flange directly above the bend against which the inclined portion is bent deflected inwardly 90 for indenting and contracting the side wall of the container along a line parallel with and directly beneath said bead for securely holding the cover on the container body.

2. A receptacle including in combination, 95 a body portion, having a cylindrical wall and an inturned bead at its upper edge, a cover for said body portion having a depending flange, and a central depression 100 forming a U-shaped pocket with substantially vertical walls adapted to receive said bead with said vertical walls frictionally engaging the inner and outer portions of said bead, a sealing material in the upper portion of said pocket, the lower edge portion of said flange being bent upwardly and inwardly and against the outer face of said flange while said cover is on the receptacle, said upwardly bent portion of the flange and the part thereof directly above the bend in the flange being deflected inwardly during the bending of the flange for indenting and contracting the side wall of the body portion of the container along a line parallel with and directly beneath said bead for securely holding the cover on the container body.

110 In testimony whereof, I affix my signature.

ALFRED L. KRONQUEST.
